UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

EQUALIZING TRUCK.

Application filed July 18, 1921. Serial No. 485,432.

To all whom it may concern:

Be it known that I, JOHN A. LAMONT, a citizen of the United States, residing at Chicago, in the county of Cook and State of Illinois, have invented certain new and useful Improvements in Equalizing Trucks, of which the following is a specification.

This invention relates to equalizing trucks for railway cars and particularly to trucks of the six-wheel type.

One object of the invention is to provide a simple and efficient equalizing arrangement for railway car trucks which will transmit the loads in a manner such that the intermediate journal box will have no tendency to tilt and cause excessive wear of the parts, but will maintain said journal box in a central position to function in a normal manner at all times.

Another object is to provide an equalizing arrangement for six-wheel car trucks adapted to meet the various requirements for successful commercial operation.

These and other objects are accomplished by means of the arrangement disclosed on the accompanying sheets of drawings, in which—

Figure 1 is a fragmentary longitudinal sectional view of a railway car truck embodying my invention, some parts being shown in elevation;

Figure 2 is a sectional view taken in a horizontal plane through a side frame showing cooperation of associated parts.

Figure 3 is a sectional view taken in the plane of line 3—3 of Figure 1; and

Figure 4 is a sectional view taken in the plane of line 4—4 of Figure 1.

The various novel features of my invention will be apparent from the following description and drawings and will be particularly pointed out in the appended claims.

Referring to the figures of the drawings, it will be noted that I have disclosed my invention in connection with a railway car truck of the six-wheel type having a side frame 10 with an opening 11 for the reception of an intermediate journal box 12, the journal box being guided in its relative vertical movements with respect to the side frame by side walls 13, the latter being provided with hardened steel wearing plates 14 for minimizing the wear. This journal box 12 has spring pockets 15 at either side of the main portion of the box in which the journal 16

is located. Load carrying springs 17 are mounted in these pockets and are bridged by a spring cap 18 having a central arched portion 19 for the reception of a yoke 20. This yoke has depending arms 21 which extend downwardly through openings 22 in the spring cap 18, through the coiled springs 17 and through openings 23 in the floor of the spring pockets. The lower ends of the arms 21 of the yoke 20 are provided with openings 24 for the reception of pins 25 upon which a hanger 26 is slung. This hanger has two upstanding arms, the walls of which are spaced for the reception of the lower ends of the yoke arms 21 and are provided with openings 27 which also receive the pins 25. Pivotaly mounted in the lower horizontal portion of the hanger bracket 26 is an equalizing beam 28 upon which the inner ends of the cooperating equalizing levers 29 directly rest. The outer ends of these equalizing levers 29 are pivotally mounted, as shown at 30, and receive their loads through bolster members 31 which rest directly on said equalizing levers.

By having the equalizing beam located at a point below the journal 16, as shown, and having the equalizing levers transmitting the loads directly thereto, the journal box is maintained in its normal balanced position, any tendency for the journal box to tilt thereby being overcome. Also any abnormal wearing of the parts which would be occasioned by a tilting of the box is obviated.

It is my intention to cover all modifications of the invention falling within the spirit and scope of the following claims.

I claim:

1. In a railway car truck, the combination of a journal box, an equalizing beam mounted below the journal in said box, and equalizing levers operatively connected to said beam whereby the journal box is prevented from tilting.

2. In a railway car truck, the combination of a journal box, an equalizing beam mounted below the journal in said box, and equalizing levers connected to said beam at points below the journal box for maintaining the latter in its normal central position.

3. In a railway car truck, the combination of a journal box, an equalizing beam, and equalizing levers directly mounted on said equalizing beam at points below the

journal in said journal box for preventing the latter from tilting.

4. In a railway car truck, the combination of a journal box, a member supported thereby, an equalizing beam pivotally mounted on said member below the journal in said journal box, and equalizing levers for transmitting loads to opposite ends of said equalizing beam.

10 5. In a railway car truck, the combination of a journal box, springs carried thereby, a spring cap bridging said springs, a yoke carried by said spring cap, a hanger slung from said yoke, an equalizing beam carried by said hanger, and equalizing levers operatively connected to said beam.

15 6. In a railway car truck, the combination of a journal box having spring pockets,

20 springs mounted therein, means bridging said springs, means suspended from said bridging means, means slung to said suspended means, an equalizing beam carried by said slung means, and equalizing levers operatively connected to said equalizing beam.

25 7. In a railway car truck, the combination of a journal box, resilient means carried thereby, means supported by said springs, means slung from said spring supported means, an equalizing beam supported by 30 said slung means, and equalizing levers operatively connected to said equalizing beam.

Signed at Chicago, Illinois, this 6th day of July, 1921.

JOHN A. LAMONT.
